WITNESS:

R. S. Wise

UNITED STATES PATENT OFFICE.

CYRUS F. JENNINGS, OF WINONA, MINNESOTA.

FOLDING TABLE.

Application filed May 29, 1925. Serial No. 33,759.

To all whom it may concern:

Be it known that I, CYRUS F. JENNINGS, a citizen of the United States, residing at Winona, in the county of Winona and State of Minnesota, have invented new and useful Improvements in Folding Tables, of which the following is a specification.

This invention relates to improvements in folding tables and contemplates pairs of cross legs having bars secured within notches provided in the upper free ends of the legs and which include upon their outer sides a plurality of substantially L-shaped hooks which are adapted to be received within eyelets provided in the opposite ends of a cloth top arranged between the top bars in order that an infant may be placed upon this cloth top while washing or dressing.

Another object of my invention is the provision of a pair of offset bars secured to the outer sides of the legs and which extend upwardly therefrom and which include a pair of frame supports secured thereon having cross bars secured to the inner sides thereof for preventing the infant from falling from the cloth top and one of the cross bars has arranged upon the outer side thereof of a shelf in order that articles used in washing and dressing the infant may be placed thereon.

A further object of my invention is the provision of a shelf supported by a pair of bars having their upper ends secured to the inner sides of the legs and which shelf has its inner end received upon the pivot pin extending between the inner sides of the supporting legs.

With the above and other objects in view, the invention further includes the following novel features and details of construction, to be hereinafter more fully described, illustrated in the accompanying drawings and pointed out in the appended claims.

In the drawings:

Figure 1 is an end elevation of my invention.

Figure 2 is a top plan view thereof.

Figure 3 is a side elevation of my invention.

Figure 4 is a vertical sectional view taken through my invention when folded.

Figure 5 is an enlarged fragmentary sectional view showing the relative position of the top bars upon the upper ends of the supporting legs and the manner of securing the cloth top thereto.

Referring to the drawings in detail, wherein like characters of reference denote corresponding parts, the reference character 10 indicates a pair of supporting legs being arranged in cross relation and having a pivot bar 11 extending through the inner sections of the legs 10 when so arranged in their cross relation in order that these legs 10 may be readily and easily folded and extended upon the pivot bar 11. Each of the legs 10 has extending transversely or laterally upon their outer sides as braces 12 extending transversely upon and secured to their outer sides while a plurality of cross braces 13, 14 and 15 respectively are arranged upon the opposite and outer sides of the legs 10 in order that their ends will be held rigidly in their respective positions and hold the same against canting and sagging.

The upper ends of the supporting legs 10 have angular notches 16 therein for the reception of cross section substantially rectangular top bars 17 therein which include fastening elements in the form of nails 18 and the like for preventing their accidental displacement when so inserted or positioned within the angular notches 16. Arranged at spaced intervals along the top of the top rails 17 is a plurality of substantially elongated hooks 19 which have their transverse portions extending outwardly and downwardly therefrom and which are adapted to receive eyelets arranged at corresponding spaced intervals along the length of the edges of a cloth top 21 and which further includes rods 22 stitched or otherwise arranged without the outer edges of the cloth top in order that the operator when so as-

sembling this table will grasp the cloth surrounding the rods 22 and in so doing pull the cloth top outwardly in order to bring the eyelets 20 into registration with and 5 hook the same upon the transverse portions of the substantially L-shaped hooks 19. A pair of relatively flat bars 23 have their upper free ends pivotally secured to the inner sides of the inner pair of supporting 10 legs 10 while their lower free ends are pivoted to the outer sides of a pair of supporting bars 24 having semi-circular cut out portions 25 provided upon the outer sides and adjacent the inner end thereof and which 15 are adapted to rest upon the upper side of the pivot rod or bar 11 and which further includes a plurality of transverse strips 26 upon the upper sides of the supporting bars 24, and thus forming a shelf beneath the 20 cloth top 21. Pairs of offset bars 27 have the inner sides of their offset portions secured to the outer sides of the supporting legs and adjacent their outer ends while their vertical portions extend upwardly and 25 above the level of the cloth top 21, while pivotally secured to their upper ends is a pair of companion bars 28 having cross strips 29 arranged upon their inner sides, while one of the strips 29 has secured to its 30 underside a relatively flat platform 30 having an upstanding outer edge 31 and thus providing a secondary shelf.

In the mode of operation of the present invention is clearly apparent and manifest that owing to the pivotal association of the supporting legs 10 upon the pivot rod or bar 11 that the same may be readily and easily expanded or folded as clearly illustrated in the positions shown in Figures 1 35 and 4, respectively, that owing to the positioning of the cross section substantially rectangular shaped top bars 17 when so arranged within the angular slots 16 provided in the upper free ends of the supporting legs 40 10 which include the substantially L-shaped hooks 19 therein which receive thereon the eyelets 20 provided in the outer edges of the cloth top 21 will give all of the stress so exercised upon the top bars 17 upon the supporting legs 10 when an infant is placed 45 upon the cloth top 21. Owing to the pivotal association and supporting of the first mentioned shelf between the inner sides of the supporting legs, it may be readily and 50 easily disconnected and folded with the supporting legs 10. The offset bars 27 when so arranged upon the outer sides and adjacent the outer free ends of the supporting legs 10 and pivotally connected with companion bars 28 and which in turn have the cross bars 29 secured to their inner sides may 55 be readily and easily extended into position and extend vertically with the vertical portions of the offset bars 27 for preventing 60 the infant when so placed upon the cloth 65

top 21 from rolling and falling from the table, while the platform 30 formed on one of the cross bars 29 and including the upstanding outer edge 31 forms a shelf or platform upon which may be placed such 70 dressing articles as may be necessary while the first mentioned platform may support a basin of water and the like, as is so desirous by the user.

The invention is susceptible of various 75 changes in its form, proportions and minor details of construction, and the right is herein reserved to make such changes as properly fall within the scope of the appended 80 claims.

Having thus described my invention what is claimed is:

1. A folding table of the character described comprising pairs of cross supporting legs having a pivot bar extending through their intersections, the upper ends of the cross supporting legs including angular notches therein, a pair of rectangular top rails received within the angular slots and secured to the supporting legs, a plurality of substantially L-shaped hooks arranged at spaced intervals upon the upper sides of the top rails, a cross top having a plurality of eyelets arranged at corresponding distances along its outer edges and received upon their companion hooks, a pair of rods stitched within the outer edges of the cloth top, pairs of offset bars having their angular portions secured to the outer sides and adjacent the upper ends of the supporting legs, companion bars having their lower ends pivoted to the upper ends of the offset bars and including cross bars upon their inner sides, and a platform arranged between the inner sides of the supporting legs and beneath the cloth top.

2. A folding table of the character described comprising pairs of cross legs therefor having a pivot bar extending through their intersections, the upper ends of the supporting legs having angular notches provided therein, a pair of cross section substantially rectangular top rails received within the angular notches and secured to the supporting legs, a plurality of substantially L-shaped hooks arranged at spaced intervals upon the upper sides of the top rails, a cloth top having a plurality of eyelets arranged at corresponding distances thereon and adapted to be received upon its companion hook, a pair of rods being stitched within the outer edges of the cloth top, pairs of offset bars having their angular portions secured to the outer sides and adjacent the upper ends of the supporting legs, pairs of companion bars pivotally secured to the upper free ends of the offset bars and including cross bars upon their inner sides, a platform extending outwardly from one of the cross bars, a pair of rela-

tively flat bars having their upper ends secured to the inner sides of a pair of supporting legs, a pair of supporting rods having their outer ends secured to the lower free ends of the relatively flat bars and including semi-circular cutout portions upon their under sides and adjacent their inner ends and received upon the upper sides of the pivot bar, and a plurality of cross strips arranged upon the upper sides of the supporting rods. 10

In testimony whereof I affix my signature.

CYRUS F. JENNINGS.
